UNITED STATES PATENT OFFICE.

VICTOR CIOMEI, OF CHICAGO, ILLINOIS.

OIL DRAIN.

Application filed July 8, 1927. Serial No. 204,350.

This invention relates to improvements in oil drains which embodies among other characteristics a construction permitting drains for reservoirs to be controlled at remote 5 points.

Another object of the invention comprehends a depth gage operable in conjunction with the oil drain.

A further object of the invention contempla- 10 plates a handle member for the oil drain.

More specifically stated the oil drain is adapted to receive the gage.

Said drain is furthermore provided with openings to permit the contents of the reservoir 15 to seek its level therein whereby the oil level of the reservoir may be readily determined upon the withdrawal of the gage from the drain.

With the above and other objects in view, 20 the invention further consists of the following novel features and details of construction, to be hereinafter more fully described, illustrated in the accompanying drawing and pointed out in the appended claim.

25 In the drawing:

Figure 1 is a transverse section taken through the crank case of an internal combustion engine and illustrating the arrangement and application of the invention there- 30 with.

Figure 2 is a longitudinal sectional view of the invention per se.

Figure 3 is a sectional view taken on line 3-3 of Figure 1.

35 Referring to the drawing in detail, where- in like characters of reference denote corre- sponding parts, the reference character 10 in- 40 dicates the crank case of an internal com- bustion engine having an oil pan 11, the above being of the usual construction as embodied in the crank cases of motors of the character described.

45 It is generally known in the construction of the particular type of motor, aforesaid, that the most effective and reliable oil gage is that of a thin strip extended within the crank case, the oil level within the crank case will be indicated upon the strip.

50 In carrying out the invention it is my car- dinal purpose to utilize the aforesaid type of gage 12 and to combine therewith a housing member therefor such as indicated at 13, closed upon one end and provided with a threaded extension 14 adapted for engage- 55 ment within a drain opening 15 within the bottom of the pan 11 and disposed in align-

ment with the opening in the crank case. Said housing 13 is provided with handle por- 60 tions 16 to permit the same to be easily ro- tated in either direction. When the threaded extension 14 is removed from the opening 15 the contents of the crank case will be drained, thereby obviating the usual necessity of 65 crawling beneath a motor vehicle and loosening a cap screw to accomplish this purpose which often proves disastrous in the event 70 that the oil finds its way up the sleeve. The gage 12 is provided with a knob 17 upon the outer extremity thereof and a tapered por- 75 tion 18 disposed within a seat 19 having com- munication with the bore of the housing 13. An enlarged portion 20 provided adjacent the outer end of the housing is adapted to 80 strengthen the same at the point wherein the same will more frequently rub or chafe 85 against the walls of the opening in the crank case. The lower portion of the housing is furthermore provided with a multiplicity of 90 openings 21 having communication with the bore thereof in order that contents of the pan 80 may seek its level within the housing. The gage 12 when removed from the housing will 95 indicate the oil level within the crank case. It is thus to be noted that essential and effec- tive means have been combined to produce an 100 oil drain capable of being operated at a remote point from the oil drain in the crank case and of the gage operable in conjunction therewith. The construction involved will permit the same to be manufactured at small 90 cost and hence appear upon different makes 105 of automobiles as a decided improvement and sales getter.

The invention is susceptible of various 95 changes in its form, proportions and minor details of construction and the right is herein reserved to make such changes as properly fall within the scope of the appended claim.

Having thus described the invention, what 100 is claimed is:

An oil drain and gauge for use within the crank case of an internal combustion engine comprising a tubular member having per- 105 forations in the periphery thereof adjacent one end, said tubular member having a closed end adjacent said perforations having screw threads on the periphery thereof whereby said end may be fitted into the drain opening in the crank case, said tubular member having an enlarged portion on the periphery thereof 110 at the end thereof opposite said end having said perforations adjacent thereto whereby

said enlarged end may be extended through an opening in the upper portion of said crank case, a handle fitted at the outer end of said enlarged portion, said tubular member having a tapered portion on the inner periphery thereof at said enlarged end, a relatively thin gauge member extended through said tubu-

lar member having a conical portion on the outwardly disposed end thereof whereby said conical portion may be seated on said valve seat to retain said gauge in said tubular member.

In testimony whereof I affix my signature.
VICTOR CIOMEI.
